DESIGN FOR A COMBINED CRACKER AND PICK

Leopold Roos, New York, N. Y.

Application May 17, 1939, Serial No. 85,040

Term of patent 3½ years

To all whom it may concern:

Be it known that I, Leopold Roos, a citizen of the United States of America, residing in New York city, in the Borough of Manhattan, county and State of New York, have invented a new, original, and ornamental Design for a Combined Cracker and Pick, of which the following is a specification, reference being had to the accompanying drawing, forming part thereof, wherein

Figure 1 is a front view of a combined cracker and pick showing my new design.

Figure 2 is a side view of the cracker member thereof.

Figure 3 is a side view of the pick member of the combined cracker and pick shown in Figure 1.

I claim:

The ornamental design for a combined cracker and pick, substantially as shown.

LEOPOLD ROOS.
